UNITED STATES PATENT OFFICE.

JOSEPH N. MILLER, OF BRAINERD, MINNESOTA.

COMBINED SETTEE AND TABLE.

Application filed September 13, 1922. Serial No. 587,879.

To all whom it may concern:

Be it known that I, JOSEPH N. MILLER, a citizen of the United States, residing at Brainerd, in the county of Crow Wing and 5 State of Minnesota, have invented new and useful Improvements in Combined Settees and Tables, of which the following is a specification.

The object of my said invention is the 10 provision of a simple, strong and easily manipulated device, susceptible of being reduced by folding to a compact state so as to be carried in an automobile body or on an automobile running board, and adapted to 15 be expeditiously and easily unfolded and set up for use either as a settee or a table.

To the attainment of the foregoing, the invention consists in the improvement as hereinafter described and definitely claimed.

20 In the accompanying drawings, forming part of this specification:—

Figure 1 is a front elevation of my improvement, as set up, for use as a settee.

25 Figure 2 is an end elevation of the same. Figure 3 is a vertical transverse section taken in the plane indicated by the line 3—3 of Figure 1.

Figure 4 is an end elevation showing the device, as set up, for use as a table.

30 Figure 5 is an inverted plan view of the same.

Figure 6 shows an end elevation of the device, as folded, for convenient carriage in, or on, an automobile, to be used incident to an 35 outing.

Similar numerals of reference designate corresponding parts in all of the views, of the drawings.

The major portion of my novel device is 40 preferably, though not necessarily, of appropriate wood, and includes spaced major members 1 in parallelism, legs 2 and a cross piece 3 fixedly connecting the same together, curvilinear members 4 and slats 5 fixedly 45 connecting the same together, leaves 6, 7 and 8, and legs 9 as well as the turn button 10.

In addition to the elements indicated constructed preferably of wood, the device comprises links 11 and 12, longitudinally slotted 50 straps 13 and 14, a latch 15 and keeper 16, brackets 17 and connections all of which are preferably of metal.

The leaf 6 is fixedly and permanently 55 connected to the edges of the members 1,

and the said members 1 are provided with sockets 17*, Figure 5, while the legs 2 are provided with sockets 18, Figures 3 and 4. The leaf 7 is provided at its inner side with dowel pins and when the leaf is used 60 as a settee back the said dowel pins are arranged in the sockets 18 of the legs 2, while when the leaf is used as a part of a table top, Figures 4 and 5, the said dowel pins are arranged in the sockets 17* of the members 1. Also in the use of the leaf 7 as shown in Figures 4 and 5, the turn-button 10 is swung on its connection 19, Figure 5 so that its end portions will rest under the fixed leaf 6 and a fixed cross bar 6* on the 70 members 1, Figures 1, 2 and 4-6. The leaf 8 bearing cleats 8* is designed primarily for use as a part of the table top, and it is detachably fastened in position by the latch 15 and keeper 16, the latter carried by a 75 cross bar 20. The legs 2 are connected with the members 1 through the medium of the pivotally attached links 11 and 12, and hence the legs 2 are adapted to be swung from the position shown in Figures 2 and 80 6 to that shown in Figure 4 and vice versa. The members 4 are pivotally connected at 25 to the members 1 so as to be capable of being positioned between the members 1, Figure 6, or extended laterally relative 85 thereto as shown in Figures 1-5. The slotted straps 13 are pivotally connected to the brackets 17 on the members 1, and their slots receive headed and threaded bolts 26 on the members 4. Wing nuts 26* on the 90 bolts 26 serve to adjustably fix the straps 13 to the members 4. The legs 9 are pivotally connected at 27 to the members 4 so as to be capable of being swung from the 95 working position shown in Figures 1-3 to the idle position shown in Figures 4-6 and vice versa. The slotted straps 14 are pivotally connected to the members 4 and their slots receive headed pins 28 on the inner sides of the legs 9.

100 It will be apparent from the foregoing that when reduced to the folded state shown in Figure 6 my novel device is very compact and may, therefore, be conveniently carried on the running board of an automobile or in the body at a point back of the front seat and this without crowding the occupants of the back seat. It will also be noted that the device is light and is therefore adapted to be easily removed from the 105 110

automobile and quickly and easily adjusted to form a settee as in Figures 1-3 or a table as in Figures 4 and 5.

When the device is used as a settee, cushions from an automobile may be and preferably are superimposed on the slats 5 to render the settee high enough for adults.

After use of the device as a settee or as a table it may obviously be folded into the state shown in Figure 6 for convenient transportation or storage; all adjustments being effected without the assistance of tools.

I have entered into a detailed description of the construction and relative arrangement of the parts embraced in the present and preferred embodiment of my invention in order to impart a full, clear and exact understanding of the said embodiment. I do not desire, however, to be understood as confining myself to the specific construction and relative arrangement of parts inasmuch as in the future practice of the invention various changes and modifications may be made such as fall within the scope of my invention as defined in my appended claims.

Having described my invention, what I claim and desire to secure by Letters-Patent, is:—

1. A foldable combined settee and table comprising spaced major members having dowel sockets, a leaf arranged at right angles to the major members and permanently connected to the outer edges thereof, swinging members pivotally connected to the inner or opposed sides of the major members, means connecting the swinging members together and adapted to form a seat, legs pivotally connected to the swinging members, slotted straps connecting the major members and the swinging members, slotted straps connecting the swinging members and their legs, legs associated with the major members and having dowel sockets in their outer edges, swinging links connecting the major members and said legs, and a shiftable leaf provided with dowel pins complementary to said sockets and adapted for

use on the outer edges of the major members to form part of a table top and for use on the outer edges of the last mentioned legs to form a settee back. 50

2. A foldable combined settee and table comprising spaced major members having dowel sockets, a leaf arranged at right angles to the major members and permanently connected to the outer edges thereof, swinging members pivotally connected to the inner or opposed sides of the major members, means connecting the swinging members together and adapted to form a seat, legs pivotally connected to the swinging members, slotted straps connecting the major members and the swinging members, slotted straps connecting the swinging members and their legs, legs associated with the major members and having dowel sockets in their outer edges, swinging links connecting the major members and said legs, and a shiftable leaf provided with dowel pins complementary to said sockets and adapted for use on the outer edges of the major members to form part of a table top and for use on the outer edges of the last mentioned legs 55 60 65 70 75

to form a settee back, in combination with bars arranged at right angles to the major members, one of said bars in spaced relation to the permanent leaf, a keeper on the other bar, and an auxiliary leaf with cleats, adapted to be opposed to the outer edges of the major members and having a latch detachably engaging said keeper. 80

3. A foldable combined settee and table comprising major members, a leaf fixed with respect thereto, a seat hingedly connected to the major members and having foldable legs, foldable table legs connected with the major members, and a shiftable leaf for association with the major members to form part of a table top and for association with the table legs to form a settee back, said elements having means for the attachment of the shiftable leaf in the said relations. 85 90

In testimony whereof, I affix my signature. 95

JOSEPH N. MILLER.
